CLAIM

The ornamental design for a polishing or grinding pad assembly with abrasive disks, reinforcement and pad, as shown and described.

DESCRIPTION

FIG. 1 is a bottom perspective view of a polishing or grinding pad assembly with abrasive disks, reinforcement and pad embodying my new design in accordance to a first embodiment;

FIG. 2 is a bottom plan view thereof;
FIG. 3 is a top plan view thereof;

FIG. 4 is a front elevation view thereof;
FIG. 5 is a rear elevation view thereof;
FIG. 6 is a right side elevation view thereof;
FIG. 7 is a left side elevation view thereof;
FIG. 8 is an enlarged and partial cross-sectional view thereof showing the abrasive disks and reinforcement pad with parallel surfaces, as taken along line 8-8 in FIG. 3; and
FIG. 9 is an enlarged and partial cross-sectional view thereof showing the abrasive disks and reinforcement pad with tapered surfaces, as taken along line 8-8 in FIG. 3.
FIG. 10 is a bottom perspective view of a polishing or grinding pad assembly with abrasive disks, reinforcement and pad embodying my new design in accordance to a second embodiment;
FIG. 11 is a bottom plan view thereof;
FIG. 12 is a top plan view thereof;
FIG. 13 is a front elevation view thereof;
FIG. 14 is a rear elevation view thereof;
FIG. 15 is a right side elevation view thereof;
FIG. 16 is a left side elevation view thereof;
FIG. 17 is an enlarged and partial cross-sectional view thereof showing the abrasive disks and reinforcement pad with parallel surfaces, as taken along line 17-17 in FIG. 12; and,
FIG. 18 is an enlarged and partial cross-sectional view thereof showing the abrasive disks and reinforcement pad with tapered surfaces, as taken along line 17-17 in FIG. 12. The broken lines in the drawings illustrate portions of the polishing or grinding pad assembly with abrasive disks, reinforcement and pad that form no part of the claimed design.
